UNITED STATES PATENT OFFICE.

CHARLES ALGERNON PARSONS, STANLEY SMITH COOK, AND LOUIS MORTIMER DOUGLAS, OF NEWCASTLE-UPON-TYNE, ENGLAND; SAID COOK AND SAID DOUGLAS ASSIGNORS TO SAID PARSONS.

GEAR-TRAIN.

1,332,061.

Specification of Letters Patent. Patented Feb. 24, 1920.

Application filed May 15, 1918. Serial No. 234,787.

To all whom it may concern:

Be it known that we, CHARLES ALGERNON PARSONS, STANLEY SMITH COOK, and LOUIS MORTIMER DOUGLAS, all subjects of the King of Great Britain and Ireland, and all residing at Heaton Works, Newcastle-upon-Tyne, in the county of Northumberland, England, have invented certain new and useful Improvements in Gear-Trains, of which the following is a specification.

The present invention relates to gear trains having single or multiple reduction ratios of the type in which an intermediate wheel is operated by one or more pinions, and has for its object to arrange the gear wheels and pinions so that the forces acting upon the intermediate pinion shaft will not tend to alter its alinement.

The invention consists in a gear train in which power is transmitted from one shaft through an intermediate shaft to a driven shaft, in so disposing the axis of the driving shaft or shafts relatively to the axes of the intermediate shaft and the driven shaft that the resultant reaction between the first interengaging gear pair or pairs and the reaction between the second interengaging gear pair act in substantially parallel lines.

The invention further consists in a gear train comprising a primary pinion or pinions driving a primary gear wheel which is co-axial with a secondary pinion driving a secondary gear wheel, the axes of the pinions and driven member being so arranged that the line of action of the force acting between the primary pinions and the primary gear wheel is substantially parallel to the direction of the reaction between the secondary pinion and the secondary gear wheel.

The invention further consists in a gear train comprising a primary pinion driving a primary gear wheel which is co-axial with a secondary pinion driving a secondary gear wheel, in which the members are so arranged that the plane passing through the axes of the primary pinion and the primary gear wheel makes with the plane passing through the axes of the intermediate pinion and the secondary gear wheel an angle which, measured in the direction of rotation opposite to that of the secondary pinion, is substantially equal to the sum of the angles of slope of the primary gear teeth and of the secondary

gear teeth in the plane transverse to the axes.

The invention also consists in the improvements in gear trains hereinafter described.

Referring to the accompanying drawings:

Figure 1 is a view of a double reduction gearing constructed according to the invention.

Fig. 2 is an enlarged view showing the slope of the teeth at the point of contact.

Fig. 3 is a diagram showing the forces acting on the intermediate shaft.

Fig. 4 is a view showing a modified double reduction gearing in which the resultant forces acting on the intermediate shaft are vertical.

Fig. 5 is a diagram showing the resultant forces.

Fig. 6 is a view of the triple reduction gearing in accordance with the invention; while

Fig. 7 is a diagram showing the forces acting on the intermediate shafts.

Fig. 8 is a diagram showing the forces acting in a case in which two primary pinions are employed driving a single primary wheel and secondary pinion.

In carrying the invention into effect as illustrated in Figs. 1 to 3 as applied to a double reduction gear system, such, for example, as is described in British patent application No. 11,046 of 1916, the drive is transmitted by means of a shaft *a* carrying a primary pinion *b* engaging with a primary gear wheel *c* mounted on a shaft *d* which carries a secondary pinion *e* engaging with a secondary gear wheel *f* on the driven shaft *g*. The pinions and gear wheels are preferably of the double helical type.

In a gear pair the turning force applied from the driving to the driven member is tangential, but owing to the slope of the teeth of the members of the pair at the point of contact, see Fig. 2, there is in all cases a radial component and consequently a non-tangential reaction between the interengaging teeth. The direction of this reaction (in a plane transverse to the axes) depends upon the slope of the teeth at the point of contact, that is to say, it depends upon the angle *z* between the common tangent *o t* to

the teeth faces at the point of contact o and the common radial line $r r$ of the interengaging gear wheels.

The intermediate shaft is retained in place by the reactions of its supporting bearings $h h$, and as these bearings must have a running clearance the eccentric position which each journal takes up in its bearing is determined almost solely by the direction 10 of the force acting upon that journal. It will therefore be seen that if the force acting on the shaft at one end has a different radial direction from that acting on the other end, the shaft will not be parallel to its bearings and will consequently be out of alignment with the teeth with which it engages.

It will be seen, however, that if the members of the train are arranged in accordance 20 with this invention, *i. e.* so that the angle β between the common radial lines of the first gear pair and of the second gear pair respectively is equal to the sum of the angles of slope α_1, α_2 of the teeth of these gear 25 pairs; the reaction between the primary pinion b and primary gear wheel c and the reaction between the secondary pinion e and secondary gear wheel f will have parallel lines of action as illustrated at Fig. 3; and 30 the forces on the respective journals of the intermediate shaft, although probably different in magnitude, will have the same radial direction and consequently there will be no harmful tendency to displacement of 35 this shaft from its correct alignment.

In addition to the teeth reactions referred to above, the only other force to be considered is the weight of the intermediate shaft d , which shaft will preferably be provided 40 with a balance weight k , Fig. 4, so that at all loads the reactions at the journals of the shaft will have substantially parallel lines of action and will consequently tend to retain the shaft in correct alignment with its 45 bearings.

Fig. 5 indicates the way in which the gear must be arranged in order that the reactions shall be in a vertical direction. The angle α_1 between the horizontal and the plane passing 50 through the axes of the shaft d and the gear wheel f must be equal to the angle α_1 .

In the form of the invention shown in Figs. 6 and 7, the driving shaft a carries pinions b driving gear wheels c and the shaft d , which also carries the pinions e driving gear wheels f and a shaft m , which also carries pinions l engaging with the gear wheels n on the driven shaft p . Counterweights k q are provided on the intermediate shafts. 60 In this case all the forces acting on the two intermediate shafts are vertical, as shown in Fig. 7.

In the diagram, the vertical lines 1, 2 show resultant forces acting on the intermediate shaft d , while the lines 3, 4 show

the forces acting on the intermediate shaft m . In this case it will be seen that with the directions of rotation as shown by the arrows, the resultant forces on the intermediate shaft d act vertically downward; and in 70 this case the balance weight k may conveniently be omitted.

In the diagram shown in Fig. 8, two primary pinions 1, 2 operate the primary gear wheel 3. The axes of the primary pinions 75 are so disposed that the resultant of their reaction upon the primary wheel represented by the line 4 acts in a direction parallel to the reaction between the secondary pinion 5 and the secondary wheel 6, this reaction being represented by the line 7.

Having now described our invention, what we claim as new and desire to secure by Letters Patent is:—

1. A gear train comprising a driving 85 shaft, an intermediate shaft, a driven shaft, a gear pair between the drive shaft and the intermediate shaft, and a gear pair between the intermediate shaft and the driven shaft, the axis of the driving shaft being so disposed relatively to the axes of the intermediate shaft and the driven shaft that the resultant reaction between one interengaging gear pair and the reaction between the succeeding interengaging gear pair act in 90 substantially parallel lines, substantially as described.

2. A gear train comprising a primary pinion, a primary gear wheel, driven by the primary pinion, a secondary pinion coaxial with 100 the primary gear wheel, a secondary gear wheel driven by the secondary pinion, the axes of the pinions and secondary gear wheel being so arranged that the line of action of the force acting between the primary pinion 105 and the primary gear wheel is substantially parallel to the direction of the reaction between the secondary pinion and secondary gear wheel, substantially as described, the primary pinion drive in whole or in part being displaced about the periphery of the primary gear wheel driven by it in relation to the plane passing through the axes of the secondary pinion on the shaft of said primary gear wheel and the secondary gear 110 wheel driven by said secondary pinion.

3. A gear train comprising a primary pinion, a primary gear wheel driven by the primary pinion, a secondary or intermediate pinion coaxial with the primary gear wheel, 120 a secondary gear wheel driven by the secondary pinion, in which the members are so arranged that the plane passing through the axes of the primary pinion and the primary gear wheel makes with the plane passing through the axes of the intermediate pinion and the secondary gear wheel an angle 125 which, measured in the direction of rotation opposite to that of the secondary pinion, is substantially equal to the sum of the angles 130

of slope of the primary gear teeth and of the secondary gear teeth in the plane transverse to the axes, substantially as described, the primary pinion drive in whole or in part 5 being displaced about the periphery of the primary gear wheel driven by it in relation to the plane passing through the axes of the secondary pinion on the shaft of said pri-

mary gear wheel and the secondary gear wheel driven by said secondary pinion. 10

In testimony whereof we have signed our names to this specification.

CHARLES ALGERNON PARSONS.

STANLEY SMITH COOK.

LOUIS MORTIMER DOUGLAS.
